DESIGN FOR AN ELECTRIC HEATER FOR HAIR WAVING

Harry Bonat, New York, N. Y., assignor to Harry
Bonat and Samuel Bonat, doing business as
Samuel Bonat and Bro., New York, N. Y.

Application January 10, 1935, Serial No. 54,786

Term of patent 7 years

To all whom it may concern:

Be it known that I, Harry Bonat, a citizen of the United States and resident of New York, Borough of Manhattan, and State of New York, have invented a new, original, and ornamental Design for an Electric Heater for Hair Waving, of which the following is a specification, reference being had to the accompanying drawing, forming a part thereof.

Figure 1 is a front elevational view of an electric heater for hair waving showing my new design;

Figure 2 is a side elevational view of the same; and

Figure 3 is a top plan view of the same.

I claim:

The ornamental design for an electric heater for hair waving, substantially as shown.

Signed at New York, in the Borough of Manhattan and State of New York, this 5th day of January, A. D. 1935.

HARRY BONAT.
